ALLEN B. DU MONT, OF UPPER MONTCLAIR, NEW JERSEY, ASSIGNOR TO DE FOREST
RADIO COMPANY, OF PASSAIC, NEW JERSEY, A CORPORATION OF DELAWARE

ULTRA-HIGH FREQUENCY GENERATING SYSTEM

Original application filed November 26, 1928, Serial No. 321,846. Divided and this application filed March 5, 1930. Serial No. 433,209.

This invention relates to improvements in radio circuits and vacuum device therefor.

One of the objects of this invention is the provision of a new form of electron discharge device in which the usual plate thereof is made in the form of a coil of wire and which, in conjunction with the grid coil, provide the inductively related coils by means of which the plate and grid circuits are associated to provide a feed back circuit.

10 A further object of this invention is the provision of an electron discharge device and circuits therefor which is particularly adapted for the generation of exceedingly short waves.

15 A further object of this invention is the provision of a short wave or high frequency generator and connections therefor which are exceedingly simple and adapted for extreme compactness.

20 These and other objects will appear from the following disclosure are secured by means of this invention.

Referring to the drawing;

25 Fig. 1 is a diagrammatic illustration of a standard form of transmitting circuit employing the feed back principle;

30 Fig. 2 is a diagrammatic illustration of the improved vacuum device of this invention and the circuits therefor, whereby extremely high frequencies may be generated.

35 Although this invention is disclosed as applied to a transmitting system, it is to be distinctly understood that the principles thereof are applicable to receiving systems, and it is intended that the claims cover both.

40 One of the difficulties encountered in producing electron discharge devices which will oscillate at extremely high frequencies is the capacity effect of long leads connecting the electrodes of the device with the other circuit instrumentalities, and in addition, the effect caused by the resistance of these leads. In producing a vacuum device which will oscillate at a fraction of a wave length the ca-

pacity of these leads and of the electrodes, although exceedingly small become of major importance, and in fact, the determining factor which limits the frequency at which the device can be made to oscillate. This invention contemplates the idea of making the usual plate and grid electrodes form the primary and secondary of the transformer by means of which the output energy in the plate circuit is fed back to the input or grid circuit. By employing these two electrodes for this purpose it is possible to eliminate the long leads, and in fact, any leads at all. This thought is true where the device is made for the particular purpose of generating currents of a single high frequency where it is not necessary to provide any capacity adjusting means to tune the two circuits. Another highly important advantage of this arrangement is that the tube becomes much more sensitive because of the combined electrostatic and electro-magnetic control of the electrons by reason of the presence of the currents in the two coil electrodes within the vessel.

45 A standard transmitting circuit is shown in Fig. 1 for purposes of comparison. The oscillating audion is shown with the exhausting vessel 1 taking the plate anode 2, grid 3 and filament or cathode 4 supplied from the current source 5. The anode is connected by wire 6 to one terminal of the current source 7, the other terminal of which is connected by wire 8 to the inductance 9. The other terminal of the inductance 9 is connected to one terminal of the grid inductance 11 which has its other terminal connected to the grid 3 by wire 12. A lead 10 connects the cathode circuit to a point between the inductances 9 and 11. The antenna circuit is shown comprising the antenna 13 connected to one terminal of the inductance 14, the other terminal of which is grounded. The inductances 9 and 11 are closely associated with the inductances 14. A short circuiting wire in-

cluding a switch 16 is provided by means of which a number of turns of the inductance 14 may be short-circuited upon the closing of the switch 16 to detune the antenna circuit. An audion circuit of this type provides a source of alternating current which is sent over the antenna as a continuous wave, the continuity of which may periodically interrupted by the closing of switch 16 for the purpose of transmitting intelligence.

When employing an arrangement of this nature for the production of exceedingly high frequencies it is found that the upper limit of frequency is determined by the capacity inductance and resistance characteristics of the leads necessary to connect the audion device to the external circuit instrumentalities. To overcome this difficulty it is proposed to make the grid and plate electrodes perform the function of the inductances 9 and 11 (Fig. 1).

Referring to Fig. 2 the electron discharge device is shown comprising an exhausted vessel 17 having the reentrant stem tube 18. The plate electrode which is usually in the form of a sheet of metal is shown in this case comprising a coil of wire 21 wound upon the insulating supports 19 and 20. The grid electrode is shown as the usual wire coil, but in this case, also supported upon insulating supports 23 and 24. The insulating supports 20, 24, 23 and 19 are supported upon wires secured to the stem tube 18. These insulating supports have been indicated as secured to the supporting wires by means of the black marks indicating a joint as shown at 20^a and 19^a. The specific features of construction are of no great concern here since they may take a number of forms. For instance, the insulating supports to extend directly to the stem tube and be secured therein and then leads taken off directly from the plate and grid electrodes. The grid electrode 22 is connected by the wire 41 to the wire support 41^a and the plate electrode 21 is connected by the wire 25 to the wire support 25^a. The cathode is shown at 40 having the leads 31 which connect it to the current source 32. Supporting wire 41^a is connected to the wire 34, and supporting wire 25^a is connected to the wire 26. A wire 33 extends from the positive side of the current source 32 and an adjustable condenser is placed across the wires 34 and 33. Wire 26 is connected to the positive side of the current source 27, the negative side of which is connected to one terminal of the inductance 28. The other terminal of the inductance 28 is connected by a wire 30 to the positive side of the current source 32. A variable condenser is connected across the wires 26 and 30. The antenna system is shown comprising the antenna 36 and inductance 37 which is grounded. As before, a short circuiting circuit is provided for a number of turns of the inductance 37 and has

a switch 38 therein. The features of this invention will be at once apparent. Instead of employing inductances 9 and 11 by means of which the plate and grid circuits are associated to provide a feed back of energy the plate electrode 21 and the grid electrode 22 are employed as these inductances and are associated with each other within the evacuated vessel. The inductance 28 is provided as a means through which the oscillating energy may be delivered for any use. The condenser 29 is provided to tune the plate circuit of the device to vary the frequency of the current generated while condenser 35 controls the feed back of energy, but it is at once apparent that when the device is made to generate one frequency only these condensers can be eliminated by designing the device to have the proper capacity to generate the desired frequency. Likewise, other means of removing the energy generated may be employed in place of the inductance 28, which could consist of a coil surrounding the tube. This device readily lends itself to extreme compactness and the few leads that are needed may readily be reduced to a minimum of length. The vacuum device becomes completely within itself, with the exception of the energy source, a generator of high frequency currents. It is, of course, apparent that the device is not necessarily limited to extremely high frequencies since lower frequencies could be generated thereby. An additional advantage of the device is that the currents flowing in the grid and plate circuits will flow through the grid and plate electrodes within the vessel and being closely associated with the cathode will aid in the control of the electrons through electro-static and electro-magnetic effects.

I am well aware that many changes in the details of construction, relative arrangement of parts, and circuit connections will readily occur to those skilled in the art, and I do not therefore desire to be strictly limited to the illustrations given, but rather to the principle and scope of this invention.

This case is a division of application Serial No. 321,846, filed November 26, 1928.

What is claimed:

1. A combination as described for generating ultra-high frequency currents comprising an electron discharge device having a cathode and coiled grid and plate electrodes each serving as an open ended inductance, means for energizing said cathode, a circuit including one of said electrodes, a source of energy on said cathode and a circuit including the other of said electrodes and said cathode whereby a generator of high frequency currents is produced in which the two electrodes serve as the sole means for inductively coupling the input and output circuits of said device.

2. In a combination as described, for gen-

erating ultra-high frequency currents, an evacuated vessel, a cathode within said vessel, a coiled grid serving as an open ended inductance and coiled plate electrode serving as an open ended inductance associated with said cathode, a grid cathode circuit, a plate cathode circuit, means for energizing said cathode, and means for tuning each of said circuits whereby a generator of oscillations is provided in which the plate and grid electrodes serve as the sole means for inductively coupling the input and output circuits.

3. In a combination of the type described for generating ultra high frequency currents, an evacuated vessel, a cathode within said vessel, means for energizing said cathode, a grid and plate electrode in the form of a wire coil associated with said cathode, an output circuit including said plate electrode as an open ended inductance and said cathode whereby the plate and grid electrodes serving as the sole means to inductively couple the input and output circuits.

4. In an arrangement for generating ultra high frequency currents, the combination comprising an exhausted vessel, a cathode, an inductively wound grid and an inductively wound anode within said vessel, an output circuit connected between said anode and cathode, an input circuit connected between said grid and cathode, including said grid as an open ended inductance, and means for tuning said input and output circuits, said grid and anode acting as means for inductively coupling the input and output circuits.

5. Means for generating ultra high frequencies comprising an electron emitting cathode, an anode in the form of a coil having its individual turns insulatingly spaced apart, a control grid in the form of a coil having its individual turns insulatingly spaced apart, circuit connections for connecting only one end of said grid to said cathode whereby said grid operates as an open ended inductance, and means for connecting said anode to said cathode in inductive relation to said grid.

50 6. Means for generating ultra high frequencies comprising an electron emitting cathode, an anode in the form of a coil having the individual turns insulatingly spaced apart, a control grid in the form of a coil having the individual turns insulatingly spaced apart, circuit connections for connecting only one end of said anode to said cathode, whereby said anode operates as an open ended inductance, and means connecting said grid to said cathode in inductive relation to said anode.

7. Means for generating ultra high frequencies comprising an electron emitting cathode, an anode in the form of a coil having the individual turns insulatingly spaced

apart, a control grid in the form of a coil having the individual turns insulatingly spaced apart, a connection from one end of said anode to said cathode whereby said anode operates as an open ended inductance, said grid and anode being mounted in inductive relation.

In testimony whereof I have hereunto set my hand on this 25th day of February, A. D. 1930.
